Primary Examiner — Kevin K Rudzinski(74) Attorney, Agent, or Firm — Dunlap Bennett & Ludwig, PLLC(57) CLAIM

The ornamental design for a shirt with a zippered opening, as shown and described.

DESCRIPTION

FIG. 1 is a front left perspective view of the shirt with the zippered opening, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly-sized broken lines shown in the drawings depict end portions of a sleeve that form no part of the claimed design.

The unevenly-sized broken lines define the bounds of the claimed design and form no part of the claimed design.
